Elomin J. Key of Lowell Mass.
Assignor to Lowell Manufacturing Company
Letter Patent No. 1361 Dated Dec 18 1860

The schedule referred to in these Letters Patent is making part of the same Schedule when it may concern:

Be it Known, that I, Elomin J. Key of Lowell in the County of Middlesex and State of Massachusetts, have originated, and designed, a new Pattern for Carpets or other Fabrics, of which the following is a full, clear, and exact description, reference being had to the accompanying drawings, making part of this specification.

Figures A and B, are composed of small regular figures surrounded by a scalloped band. Figs. 1 and 2, are composed of bands of dots intersected at right angles to Key word, the whole being surrounded by a scalloped band. Small blocks of various shapes occupy the space between figures A & B, 1 & 2. The colors employed for the different portions of the design may be varied to suit the taste and wish of the manufacturer.

Claim

What I claim as my invention and desire to secure by Letter Patent, is—

The design or pattern for carpets or other fabrics, herein set forth. I also claim the particular form of the small work shown in figures A, B, 1 & 2, in the drawings.
